KNOCK-DOWN STAND FOR DISPLAY TRAYS

Herman H. Williams, Minneapolis, Minn., assignor to Northrup, King & Company, Minneapolis, Minn., a corporation of Minnesota

Application July 27, 1936, Serial No. 92,742

7 Claims. (Cl. 211—128)

My invention provides a simple, rigid, and highly efficient stand or skeleton-like support for display trays; and, generally stated, the invention consists of the novel devices, combinations 5 of devices and arrangement of parts hereinafter described and defined in the claims. The improved stand is adapted to support trays differing in character and useful purpose, but primarily has been designed to support stepped 10 trays such as used in the sale of seeds and the like.

Stands of the above character, when erected for use, while light in weight, are bulky in respect to the space occupied thereby. These 15 stands are frequently furnished by the wholesale seed house for distributors located at various different remote parts of the country. To avoid the excessive expense of shipment and liability of breakage of these stands, my invention provides 20 a knock-down structure in which the parts may be assembled in flatwise condition and packed in compact form, and hence, shipped by freight or express, or otherwise, at the lowest possible transportation rate. This manner of compact 25 shipment also eliminates the danger of breakage or damage to the parts and provides a structure that may be very easily and quickly erected at the place of use. The display of seeds and the like is a seasonal matter; and, hence, the knock-down stand, which is capable of being easily 30 taken apart, packed in small storage space when out of use, and then again re-erected when the time for display again arrives, is highly desirable.

35 The invention is illustrated in the accompanying drawings wherein like characters indicate like parts throughout the several views.

Referring to the drawings:

Fig. 1 is a perspective showing the stand erected and used to support two trays for the display of seeds and the like, said trays being indicated by dotted lines;

Fig. 2 is a front elevation of the improved stand, the trays being removed therefrom;

Fig. 3 is a section taken on the line 3—3 of Fig. 1, one of the trays being shown in full, cross-sectioned, and some of the parts of the stand being sectioned;

Fig. 4 is a fragmentary section taken on the line 4—4 of Fig. 3;

Fig. 5 is a section taken on the line 5—5 of Fig. 4; and

Fig. 6 is a fragmentary view partly in elevation and partly in section on the line 6—6 of Fig. 3.

The improved stand, as illustrated in the drawings, is made up of laterally spaced side frames and front and rear cross-tie members. Each side frame comprises tubular front and rear corner posts 7 and 8, rod-like post extensions 9 and 10, the upper and lower tie rods 11 and 12. The tie rods 11 and 12 are welded or otherwise rigidly secured to the tubular corner posts 7 and 8. The post extensions 9 and 10 may be, and preferably 5 are, tubular for the sake of likeness. For an 10 important purpose, which will presently appear, the post extensions 10 are much longer than the post extensions 9, while the posts 7 or 8 are of approximately the same length. The two side 15 frames are rigidly but detachably tied together by suitable cross-ties. In this preferred arrangement, the front posts 7 are connected by a single tubular cross-tie rod or member 13, while the rear legs 8 are likewise rigidly connected by two vertically spaced cross-tie rods or members 14. 20 The rigid but detachable connection between the said cross-tie rods 13 and 14 and the corner posts 25 are preferably made by coupling screws 15, best shown in Fig. 6, which are passed through perforations in the said corner posts and screw into the internally threaded ends of the tubular cross-tie rods 13 or 14, as the case may be.

The post extensions 9 are rigidly and permanently connected by cross-tie rods 16 while the inner post extensions 10 are rigidly and permanently connected by upper and lower cross-tie rods 17. The said cross-tie rods 16 and 17 may 30 be and, preferably, are tubular, and at their ends they will advisably be spot-welded to the respective post extensions.

As is now evident, the side frames will be rigidly tied together when connected by the cross-tie rods 13 and 14. When the post extensions are telescoped into the upper ends of the tubular corner posts, they will drop down as far as 40 permitted in the one instance by the cross-tie 16, and in the other instance by the cross-tie 17; and when these tied or braced post extensions are thus applied, further rigidity is given to the upper portions of the stand. To make the stand 45 easily movable on the floor, the lower ends of the corner posts are shown equipped with caster rollers 18. The extreme upper portions of the post extensions 10 may be utilized to support a display board 19, the ends of which are inserted 50 through a slight cut in the upper ends of said posts, as best shown in Fig. 4.

It is evident, from the foregoing description, that the stand may be very quickly assembled or set up and very quickly disassembled or knocked 55

down into component parts. When all of the separable parts are disconnected, they will consist of two side frames; the front post extensions 9 and permanent tie rods 16; the post extensions 10 to cross-tie rods 17 and board 19; and the three cross-tie rods 14—14 and 13. As is evident, all of these parts may be closely packed together in flat assembly and within a very small space, for the above noted purposes of shipment or storage.

The above described stand has been especially designed for supporting display trays of a form disclosed and claimed in my Patent No. 2,076,690 of April 13, 1937, entitled, "Display tray". Two 15 of such display trays are shown in Figs. 1 and 3. Each tray comprises a metal sheet 20 bent into zig-zag form to form trough-like display compartments. The lower end of the sheets 20 have down-turned flanges 21 and the upper ends of 20 said sheet have down-turned flanges 22. These flanges are adapted to be engaged in the one instance with the upper cross-tie rods 17 and the cross-tie rods 16, and in the other instance with the upper cross-tie rods 14 and cross-tie rods 13. 25 When thus supported, the trays will be obliquely held with their compartments in stepped relation, one above the other, so that articles such as seed packages placed in the compartments and projecting above the front walls of the same may 30 be simultaneously viewed by a person in front of the stand.

Preferably, the lower tray 20 is slightly narrower than the upper tray. The upper tray may 35 be as wide as possible for entrance between the post extensions, but the lower tray should be slightly narrower so that, when it is placed between the front and rear posts, there will be a little clearance permitting the fingers of the hand 40 to grip the edges thereof for the purpose of application and removal of the tray.

From the foregoing, the advantages of a device such as described are thought to have been made 45 obvious. It will also be understood that the device described as to details of construction and arrangement of parts may be varied within the scope of the invention herein disclosed and claimed.

What I claim is:

1. A stand of the kind described comprising a 50 pair of laterally spaced side frames, each comprising a front post, a rear post and horizontal tie rods rigidly connecting the respective front and rear posts, a pair of rear extension posts mounted for vertical movements on the rear posts 55 of said side frames and rigidly connected by upper and lower cross-tie connections, the lower of said cross-tie connections limiting the downward movement of said rear extension posts on the rear posts of said side frames, a pair of front extension posts mounted for vertical movements on the front posts of said side frames and rigidly 60 connected by a cross-tie connection that limits the downward movement of said front extension

posts on the front posts of said side frames, and a display rack supported at its front on the cross-tie connection of said front extension posts and supported at its rear on the upper cross-tie connection of said rear extension posts. 5

2. The structure defined in claim 1 in which the posts of said side frames are tubular and said extension posts are telescoped into the upper ends thereof.

3. The structure defined in claim 1 in which the front posts of said side frames are rigidly but detachably connected by a cross-tie connection, and the rear posts of said side frames are rigidly but detachably connected by a cross-tie connection that is higher up than the cross-tie connection between the front posts of said side frames, said last two noted cross-tie connections serving to obliquely support a second display rack. 15

4. A stand of the kind described comprising a pair of side frames each made up of a pair of 20 rigidly connected front and rear posts of approximately the same vertical length, a pair of short front post extensions mounted for vertical movements on the front post of said side frames and rigidly connected by a cross-tie, a pair of rear 25 extension posts that are relatively long as compared with said front extension posts, mounted for vertical movements on the rear posts of said side frames and rigidly connected by upper and lower cross-ties, the latter of which is on approximately the level of the cross-tie connecting said front post extensions, and a stepped tray supported on the cross-tie connection of said front post extensions and on the upper cross-tie 30 connection of said rear post extensions. 35

5. The structure defined in claim 4 in which said posts and post extensions are tubular and the latter are telescoped into the former.

6. A stand of the kind described comprising a pair of side frames, each made up of a pair of 40 rigidly connected front and rear posts, a pair of rigidly connected rear extension posts mounted for vertical movements on the rear posts of said side frames, a pair of rigidly connected front extension posts mounted for vertical movements 45 on the front posts of said side frames, said rear extension posts being longer than said front extension posts, a display rack obliquely supported at its front and rear by said extension posts, the front posts of said side frames being rigidly but 50 detachably connected by a cross-tie connection, and the rear posts of said side frames being rigidly but detachably connected by a cross-tie connection that is higher up than the cross-tie connection between the front posts of said side 55 frames, said last two noted cross connections serving to obliquely support the display rack.

7. The structure defined in claim 6 in further combination with a stepped tray supported in oblique position on the last two noted cross-tie 60 connections.

HERMAN H. WILLIAMS.
